M. WELTE & SONS, INCORPORATED, OF NEW YORK, N. Y., A CORPORATION OF
NEW YORK.

MEANS FOR SYNCHRONIZING THE OPERATIONS OF SOUND-PRODUCING INSTRUMENTS AND MOVING-PICTURE APPARATUS OR OTHER MOVING PARTS.

1,325,066.

Specification of Letters Patent. Patented Dec. 16, 1919.

Application filed June 11, 1914, Serial No. 844,574. Renewed April 17, 1918. Serial No. 229,199.

To all whom it may concern:

Be it known that I, EDWIN WELTE, a citizen of the Empire of Germany, residing at Freiburg, in the Grand Duchy of Baden, in the Empire of Germany, have invented new and useful Improvements in Means for Synchronizing the Operations of Sound-Producing Instruments and Moving Picture Apparatus or other Moving Parts, of which 10 the following is a specification, reference being had to the accompanying drawings, in which—

Figure 1 is a view, partly diagrammatic and partly in section showing a synchronizing apparatus embodying the present improvements, the valves of the synchronizing apparatus being shown in the position which they occupy when the pneumatic is not opened to atmospheric air through the 20 operation of the controlling elements;

Fig. 2 is a like view showing the positions of the parts when the record of the musical or other sound-producing instrument constituting one of the parts to be synchronized 25 is moving faster than the other moving part which is to be synchronized therewith, at the moment when the primary controlling element associated with said record has opened the primary valve controlled thereby and before the primary controlling element associated with the other moving part 30 has opened the primary valve controlled thereby.

Figs. 3 and 4 are detail representations.

Fig. 5 is a plan view of parts of the chest J particularly intended to show one way by which the links 137 and 138 may be connected to the arm 132.

Similar characters of reference denote 40 similar parts in the several views.

This invention relates generically to mechanism for synchronizing the operations of moving parts. It particularly but not exclusively relates to a mechanism for synchronizing the operations of a record controlled musical instrument—as an automatic piano, orchestrion or organ, for example—and a machine, apparatus, instrument or device appropriate for use there- 45 with. A very useful application of the present invention has reference to the synchronization of the operating of a record controlled musical instrument and a mov-

ing picture apparatus, the moving parts in such case being the traveling perforated 55 note sheet, or other device constituting the record which controls the operation of the musical instrument, and the film of the moving picture apparatus; the purpose of the invention in such case being automatically 60 to cause the production of musical or other sounds predetermined to accompany an exhibition of a photoplay or the like in proper relation to the pictures to which they severally relate. Hence, I have exemplified the 65 invention as organized for this particular application thereof. It will be understood, however, that the invention is not restricted to its application as a means for synchronizing the operation of a moving-picture apparatus and a sound producing instrument, and that it is within the spirit of the invention, and its scope as defined by the subjoined claims, to embody it as a means for synchronizing the operations of various 70 mechanisms, machines, apparatuses, or devices which may desirably be worked together and when so worked should be operated in time or harmony, one with the 75 other.

Referring now to the embodiment of the invention exemplified, which I will describe in minute detail because it represents what I now consider to be the preferred embodiment of the invention;

A designates a perforated roll or note sheet of character similar to that commonly employed as the record for controlling the operation of self-playing musical instruments. It is commonly known that such note sheets are fed over a tracker board B by means which usually comprise an air-motor C of suitable construction connected by appropriate gearing with a take-up roll, 90 D. I have not considered it to be necessary to show the musical instrument, or the mechanism by which the musical instrument is operated under control of the perforated note sheet or other record usually employed for the control of such instruments, and which mechanism, as is well known is sometimes arranged in the case of the instrument itself and at other times in a separate portable cabinet which is movable into and out of operative relation with 100 the instrument, particularly when such in-

strument is a piano or organ. Such mechanisms are well known and the means thereof for connecting the motor C thereof with the take-up roll D to feed the record over 5 the tracker board also are well known and need not be particularly described.

Whatever record is employed, it should be operated in consonance with what is hereinafter called "first controlling element." When the record is a perforated music roll or note sheet, the first controlling element is preferably embodied as a part thereof and is herein shown as comprising a series of spaced perforations 20 formed 15 along the note sheet and near one edge thereof. These perforations are of equal length and the space 21 between each pair of perforations preferably is of the same length as each perforation. The tracker 20 board B for use with such record is provided with a special aperture 22 with which the perforations 20 successively register in the movement of the record over the tracker board.

25 E designates a shaft to be synchronized with the record A. This shaft may be assumed to be the shaft to which power is applied in the feeding of the film of a moving picture apparatus of the usual or any suitable construction. Operating in consonance with this shaft is a "second controlling element" the phases of whose operation in relation to the "first controlling element" control or determine the operation 30 of mechanism, the preferred embodiment of which is hereinafter set forth, by which the relative speeds of the moving parts to be synchronized are in turn controlled. It is preferred in practice to increase or reduce 35 the speed of the record A to accord with any fluctuations in the speed of the other part to be synchronized therewith, and accordingly the mechanism exemplified by the accompanying drawings is organized to accomplish this particular purpose.

40 The particular "second controlling element" herein shown is of an electrical nature and includes a switch F which is preferably mounted on the shaft E. This particular switch has its peripheral surface provided with two oppositely-arranged conducting members 23 alternating with non-conducting members 24 and connected with each other by a conducting member 23a. As 45 associated with this switch and forming part of the "second controlling element" are two contact-arms 25, a battery 26, or other suitable source of electrical energy, an electromagnet 27 and suitable circuit connections, 50 as the wires 28 and binding posts 29, for example whereby the magnet will be energized when the contact arms 25 engage the conducting portions 23 of the switch and will be deenergized when the contact arms 55 are in contact with the non-conducting por-

tions 24 of said switch. The armature of the magnet is marked 30 and carries a self-closing valve 123.

The correlation of the perforations 20 of the "first controlling element" and the conducting portions 23 of the "second controlling element" is such that when the parts are moving in synchronism the circuit through the magnet shall be closed at the instant a perforation 20 commences to 70 register with the tracker duct 22 and shall be opened at the instant said perforation 20 passes out of registration with said duct. When, however, the record A is traveling slower than the film, or other part to be synchronized therewith, its perforations 20 are severally brought into registration with tracker duct 22 before the circuit has been closed through the magnet, and similarly if said record is traveling faster than the film, 75 or other part to be synchronized with the record, the circuit through the magnet will be closed before a perforation 20 will be brought into registration with the tracker duct: but nevertheless there will be periods, 80 due to the relative arrangement of the perforations 20 in the record A and the conducting members 23 of the switch F when the switch will be closed while a perforation 20 is in registration with the tracker duct 85 22, whether the record A be traveling faster or slower than the film: and the synchronizing mechanism has been so organized, as will be hereinafter more fully explained, 90 that (1) no change in the speed of either 95 part is effected by the synchronizing mechanism when the tracker duct 22 is opened at the same instant the switch is energized, (2) the opening of the tracker duct 22 in advance of the closing of the circuit through 100 the magnet will cause parts of the synchronizing mechanism to be affected in such manner that the connections to the motor C will become operative to effect a reduction 105 in the speed of the motor when the magnet has been energized: and (3) if said magnet 110 is energized before the tracker duct 22 has been opened, it will cause parts of the synchronizing mechanism to be affected in such manner that the connections to the motor C 115 will become operative to effect an increase in the speed of the motor when said tracker duct has been opened.

When the motor C is of a pneumatic nature, as preferred, the change in its speed is 120 controlled by correspondingly controlling the air under whose influence it is operated. For this purpose, I provide a suitable governor and mechanism, including a suitable system of pneumatically operable valves, for 125 controlling the governor. One suitable form of governor includes a valved-member indicated as a whole by the letter G. I prefer to employ a pneumatic motor of a suction nature and to utilize a slide valve as the 130

governing element therefor, and accordingly I have shown such arrangement; H being the main suction conduit; H' a valve box having an opening 31 in communication with the conduit, and also having an opening 32 which is in communication with a conduit H² which leads from the box H' to the motor C; and 33 being a slide valve whose position with relation to the opening 31 controls the suctional force to which the motor is subjected through the conduit H². The preferred form of valve actuating mechanism of the governor is indicated as a whole by the letter I and includes devices of a pneumatic nature, as ordinary suction bellows 43 and 44, for example, which are independently operable to move the valve to increase or reduce the area of the opening 31.

In the herein exemplified form of the invention, valve 33 has an outwardly-extending stem 34 by which it is connected to an oscillatory member 35 which is pivoted at 36 and has arcural teeth 37 meshed with a pinion 38 mounted on a shaft 39. The shaft 39 is provided with a ratchet 40 having two sets of teeth, 40^a and 40^b, and these sets of teeth are respectively engaged by arms or pawls 41 and 42 operable to move the ratchet to the right or left, thereby, through the described gearing, or other connecting means which may be employed in lieu thereof, moving the stem 34 and valve 33 and causing more or less of the opening 31 to be uncovered, so as to increase or reduce the speed of the motor. The pneumatics 43 and 44 are connected to the arms 41 and 42 respectively. The arms or pawls 41 and 42 are preferably held in proper relation to the teeth 40^a and 40^b by springs 41^a and 42^a, and a pair of coöperating stop elements 45 and 46 are preferably employed for each bellows 43 and 44 to control the extent of collapsing movement of said bellows, one stop, as 45, of each pair being adjustable and the other having a sound deadening surface 47.

For operating the pneumatics 43 and 44 I employ a mechanism which utilizes air having different pressures—as atmospheric pressure and less than atmospheric pressure, respectively, for example—and regulate the effects of these by a pneumatic action, under control of the primary controlling elements. The preferred embodiment of this action will now be described in detail, without, however, thereby intending to restrict the invention to the particular details which will be described.

91 and 97 designate a pair of pneumatically operable valves hereinafter called primary valves. These valves are mounted in chambers 81 and 87 respectively. Chamber 81 has ports 81^a and 81^b, through which it has communication with sources of air having different pressures, as atmospheric

pressure and less than atmospheric, for example, and valve 91 opens and closes these ports alternately. The stem of this valve is connected to a suitable pressure-operable member, as a diaphragm or membrane 105, one side of which is constantly exposed to air having less than atmospheric pressure, for example, while its other side is intermittently exposed to air having atmospheric pressure, for example, under control of the first controlling element, the said air being admitted through a duct 119 extending from the tracker duct 22 and connected with a chamber 100 by a branch 121.

Chamber 87 similarly has ports 87^a and 87^b which are opened and closed alternately by the valve 97 to thereby control communication of said chamber with said air sources. This valve operates under control of the second controlling element, its stem being connected to a suitable pressure-operable member, as a diaphragm or membrane 109, one side of which is constantly exposed to air having less than atmospheric pressure, for example, while its other side is intermittently exposed to air having atmospheric pressure, for example, admitted to a chamber 104 through port 122^a by the energizing of the magnet 27.

There is another pair of valves marked 93 and 95, hereinafter called "secondary valves". These are mounted in chambers 83 and 85 having ports 83^a and 85^a through which the chambers respectively have communication with the air of one pressure, as atmospheric, for example, and other ports 83^b and 85^b through which they respectively have communication with the air of a different pressure, as less than atmospheric, for example. Chamber 83 is connected with pneumatic 44 by a duct 148 and chamber 85 is connected with pneumatic 43 by a duct 147. Valve 93 has its stem connected to a suitable pressure-operable member, as a membrane or diaphragm 106, one side of which is constantly exposed to the air of one pressure, as less than atmospheric, for example, while its other side is intermittently exposed to the air of a different pressure, as atmospheric, for example. Valve 95 similarly has its stem connected to a suitable pressure-operable member, as a membrane or diaphragm 108, one side of which is constantly exposed to the air of one pressure, as less than atmospheric, for example, and the other side of which is intermittently exposed to the air of a different pressure, as atmospheric pressure, for example.

The pressures which open the secondary valves are substantially under control of the primary valves through an intermediate mechanism which is of a selective nature in that it includes elements whereby one secondary valve, as 95, is opened when primary valve 91 is opened first, and the other sec-

ondary valve, as 93, is opened when the other primary valve, as 97, is opened first. The selecting means are thus, broadly, under control of that moving part which is 6 in advance of the other. This selective mechanism, as herein embodied, is further characterized by the fact that neither secondary valve is opened when both primary valves are opened at the same instant and 10 still further characterized by a correlation of parts of such nature that the opening of one primary valve in advance of the other sets an appropriate actuating element of pressure controlling means into such position 15 that when the other primary valve is opened said element will be moved to operate said means to open one or the other secondary valve, in accordance with the position to which said actuating element has 20 been set.

The pressure controlling means last referred to preferably includes a pair of valves 141 and 142 which respectively control atmospheric channels 143 and 144 leading to 25 chambers 103 and 101 on one side of the diaphragms 108 and 106, respectively. The actuating element referred to is preferably an arm 132, and the means for operating this arm to cause the secondary valves to open 30 selectively, include means by which adjusting movement is imparted to the arm to set it into selecting position with relation to one or the other valve 141 and 142, according to which primary valve is opened in advance 35 of the other, and also includes means by which operating movement is imparted to the arm, the latter means including an element which is rendered effective when the second-opened primary valve, that is, the 40 primary valve associated with the lagging moving part, has been opened.

The adjusting means forming part of the selective mechanism, in the herein exemplified form of the invention, includes a pair 45 of pneumatically operable valves 92 and 96 mounted in chambers 82 and 86, respectively, and a pair of pneumatics 135 and 136 which are respectively connected to the chambers 82 and 86 by ducts 139 and 140 and are also connected to the arm 132 by links 137 and 138, respectively.

The chambers 82 and 86 have ports 82^a and 86^a, through which they may have communication with air of one pressure, as atmospheric, for example, and other ports 82^b and 86^b through which they may have communication with a source of air of different pressure, as less than atmospheric, for example.

60 Of course it will be understood that the open position of all the valves herein referred to is that position they are caused to assume in effecting change in the relative speeds of the parts to be synchronized. In 65 the present exemplification of the invention,

this occurs when the valve chambers are in communication with the source of air of less than atmospheric pressure and in such case the open position of the valves is the position in which they open their respective chambers 70 to such source of air and their closed position is that in which their chambers are opened to the atmosphere, the latter serving as well understood to restore the parts to position to be again operated.

75 The links 137 and 138 have their outer ends pivoted to the movable boards of the pneumatics 135 and 136 respectively and their inner ends are suitably pivotally connected to the arm 132 to cause said arm to 80 be adjusted toward the right, into line with valve 141 when bellows 135 is collapsed, and to be adjusted toward the left into line with valve 142 when bellows 136 is collapsed. This arm is carried by a pneumatic 130, to 85 the movable board of which one of its ends is pivoted at 133 and is held normally in a neutral position, between the lines of the valves 141 and 142, by a spring 134, the tendency of which is to return the arm to 90 its neutral position when the force exerted thereon through the pneumatic 135 and link 137 or pneumatic 136 and link 138 to move it pivotally from such position has ceased. This pneumatic 130 when collapsed, imparts 95 operating movement to the arm 132 while the pneumatics 135 and 136, when collapsed, impart adjusting movement thereto, as apparent.

100 Valves 92 and 96 are controlled by the primary valves 91 and 97 and hence by the moving parts respectively, and these valves are preferably so correlated, through intermediate interrelated connections, that neither valve 92 nor valve 96 are opened 105 when both primary valves are opened at once, but when valve 91 is opened before valve 97, valve 92 also is opened and valve 96 is locked in closed position until valve 97 has been opened, whereupon valve 96 is 110 released and valve 92 is closed; and similarly when valve 97 is opened first valve 96 is opened and valve 92 is locked in closed position until valve 91 has been opened whereupon valve 96 is closed and valve 92 115 released. This is preferably accomplished by attaching the stems of valves 92 and 96 to suitable pressure operable members as diaphragms or membranes 112 and 115, respectively, one of which, 112, is arranged 120 between two chambers 110 and 111 and exposed to air therein, and the other of which, 115, is arranged between and exposed to the air in two chambers 113 and 114, and by connecting chambers 111 and 114 with chambers 81 and 87 respectively by channels 125 and 127, for example, and chambers 110 and 113 with chambers 87 and 81, respectively, by ducts 128 and 124, for example. There is another valve, marked 94, and this 130

valve is operated to render the pneumatic 130 effective to move the arm 132 longitudinally to open valve 141 or valve 142 according to the position to which said arm has 5 been previously adjusted. In a broad sense it is under control of that moving part which is lagging behind the other moving part and hence, broadly, is under control of the primary valve associated with the lagging moving part, *i. e.*, the second-opened 10 primary valve.

In the particular herein-exemplified form of the invention, more specifically stated, the valve 94 is under the conjoint or combined control of the primary controlling 15 elements, through a correlation of parts of such nature that the air pressures which operate the pneumatic 130 are so controlled that they do not become effective upon the pneumatic 130 to move the arm 132 into position to operate either valve 141 or 142 until the controlling elements have caused both primary valves 91 and 97 to be opened. Hence, the operation of this valve actuating 20 arm 132 to open either of said valves 141 or 142 is assuredly postponed until after it has been adjusted, if the moving parts are traveling out of synchronism with each other.

30 In the particular form of the invention herein exemplified the valve 94 is mounted in a chamber 84 having ports 84^a and 84^b for airs of different pressures, as atmospheric and less than atmospheric, for example. This chamber is also connected 35 with the pneumatic 130, by a channel 131. The stem of the valve 94 is attached at one end to a diaphragm 107, one of whose surfaces is constantly exposed to air of one 40 pressure, as less than atmospheric, for example, and the other of whose surfaces is intermittently exposed to air of a different pressure, as atmospheric, for example, under control of the first controlling element. The 45 other end of said valve stem is attached to a membrane or diaphragm 118 separating two chambers 116 and 117 from each other. One of these chambers (116) is constantly 50 open—through channel 129, for example—to air of one pressure, as less than atmospheric, for example, so that this side of the diaphragm is constantly exposed to such air. The other chamber, (117) is constantly 55 open in communication with chamber 87, by duct 126 for example, whereby the side of the 60 diaphragm presented to this chamber is intermittently exposed to airs of different pressures, under control of the second controlling element. The chamber 102, on one 65 side of the diaphragm 107 is connected with the duct 119, by a branch 122, for example.

The several chambers and their valves may be conveniently embodied in the form 65 of a chest and such embodiment accordingly

is shown, the chest considered as a whole being marked J. Moreover, the present day practice, in self-playing musical instruments, for example, which utilize differences in air pressures in the operation or 70 control of the parts, favor the use of air at atmospheric pressure and air at less than atmospheric pressure, *i. e.*, under suction, and for the same reasons which cause said airs to be preferred in such instrument, I 75 prefer their use herein, although I recognize that when the present invention is embodied in an instrument of a pneumatic nature, as herein exemplified, airs of other different pressures may be employed though probably with less satisfactory results.

Accordingly, I have shown the chest J as having a conduit 80 which is under suction derived from a suitable source, not shown, and a separate conduit 90 which is 80 suitably open to the atmosphere. The chambers 81—87 are between these conduits or conductors of air currents and they severally open into the conductor 80 through their ports 81^b 87^b and into the conductor 90 through their ports 81^a 87^a. The chest also contains the chambers 100, 101, 102, 103 and 104, and these chambers are separated from the suction conduit 80 by the diaphragms 105, 106, 107, 108 and 109, respectively. It further contains the chambers 110 and 111, separated from each other by the diaphragm 112; the chambers 113 and 114, separated from each other by the diaphragm 115, and the chambers 116 and 117 separated from each other by the diaphragm 118; and also contains the channels 125, 127, 129 and 131, hereinbefore referred to. Moreover, the valves 141 and 142 are preferably mounted in chambers, 145 and 146, which are suitably open to the atmosphere and form a part of the chest.

As has already been stated, the valve 92 is connected with a diaphragm 112 arranged between chambers 110 and 111 and the valve 110 96 is connected with the diaphragm 115 arranged between chambers 113 and 114. It has also been shown that the chambers 111 and 113 are connected with the chamber 81 by the channel 125 and duct 124 respectively, 115 while the chambers 114 and 110 are connected with the chamber 87 by the channel 127 and duct 126, respectively. It will be apparent that whenever a tempo-perforation 20 registers with the aperture 22 in the tracker-board, the valve 91 will be raised thereby cutting off the chambers 111 and 113 from communication with the atmospheric conduit 90 and placing them in communication with the suction conduit 80. Accordingly 120 if the valve 91 is raised before the valve 97, the chambers 111 and 113 will be placed under suctional force while the chambers 110 and 114 still have communication with the atmospheric conduit 90. Hence the dia- 125 130

phragm 112 will be raised, thereby raising the valve 92, and opening communication of the chamber 82 with the suctional conduit, while at the same time the air forces on opposite sides of the diaphragm 115 will act to hold the valve 96 tightly in the position in which it excludes communication of the chamber 86 with the suctional conduit. The chamber 82 being now open to suction, the 16 pneumatic 135 is collapsed and hence the arm 132 is thereby moved pivotally to the right of its neutral position automatically when the first controlling element operates to permit the valve 91 to be raised before the 16 second controlling element has permitted the valve 97 to be raised.

On the other hand, when the valve 97 is raised before the valve 91, the chambers 114 and 110 will be placed under suction while 20 the chambers 113 and 111 are still in communication with the atmospheric conduit, thereby causing the valve 96 to be raised and the pneumatic 136 to be placed under suction and to move the arm 132 pivotally to 25 the left of its neutral position, while the valve 92 is held to its position in which it closes the chamber 82 and consequently the pneumatic 135 to suction.

The pneumatic 130 is only operated to 20 move the arm 132 longitudinally when both of the controlling elements are in positions in which the chambers 102 and 104 are simultaneously open to the atmosphere: for when the chamber 102 is open to the atmosphere while chamber 104 is closed against the atmosphere the relative pressures on opposite sides of the diaphragm 107 tending to raise said diaphragm are balanced by the 25 relative pressures in the chambers 116 and 117 on opposite sides of the diaphragm 118 and hence the forces which tend to raise the valve 94 are insufficient to overcome the forces which tend to hold the valve down; while on the other hand if the chamber 104 only is open to the atmosphere the diaphragm 109 will be raised and will raise the valve 97 and place the chamber 117 under suction through the duct 126, chamber 87, and port 87^b, but this results merely in a 30 balancing of the suctional forces on opposite sides of the diaphragm 118 and as the chamber 102 is not in communication with the atmosphere there is no predetermined amount of pressure exerted on the diaphragm 107 such as would raise the same and thereby raise the valve 94. Hence, the 35 adjustment of the arm 132 pivotally to the right or left of its neutral position, commences before the longitudinal movement of 40 said arm. It will be noted that the tempo-perforations 20 of the first controlling element and the conducting parts 23 of the second controlling element are of appropriate length, being such that even when the movements of the record and film are not per-

fectly synchronized, and hence it becomes necessary to either speed up or slow down the record, there will be a time in the movement of every tempo-perforation 20 when it will register with the aperture 22 in the 70 tracker board while the circuit is closed through the magnet, whereby longitudinal movement of the arm 132 after it has been adjusted to the right or left of its neutral position is assured. 75

When the arm 132 is moved longitudinally while in adjusted position at the right of its neutral position, it acts upon the valve 141 and opens chamber 108 to the atmosphere, thereby causing the diaphragm 108 to 80 be raised and to raise the valve 95 so as to open the chamber 85 to the suctional conduit. This chamber 85 being connected to the pneumatic 43 by a duct 147 said pneumatic is collapsed when the valve 48 is raised. 85 Similarly, when the arm 132 is moved longitudinally while in adjusted position at the left of its neutral position, it acts upon the valve 142 and opens the chamber 101 to the atmosphere, causing thereby the valve 93 to 90 be raised and suction to be communicated to the pneumatic 44 through the conduit 80, port 89^b, chamber 83 and duct 148.

The operation of the herein exemplified form of the invention may be recapitulated 95 as follows:—

Assuming that a record has been produced having perforations suitable to cause the production of sounds appropriate to the picture and with tempo perforations properly 100 arranged thereon, and assuming further that means of a suitable kind, not necessary herein particularly to set forth, are employed to indicate the moment at which the record shall be started, and also assuming 105 that when the record and film are started at the proper relative times but variations in the relative speeds thereof may occur through the inability of the operator of the moving picture apparatus to turn the shaft 110 E at an absolutely uniform rate of speed at all times, for example—there evidently will be times when the record and shaft E will be moved at exactly the same speed so that the first tempo-perforations in the record will 115 register with the aperture 22 at the same moment that the circuit is closed through the magnet 27 and other times when the record may be moving somewhat faster than the speed of rotation of the shaft E, and still 120 other times when the record may be moving slower than the shaft E.

When the tempo regulating perforations of the record pass over the aperture 22 of the tracker board exactly at the same moment that the conducting members 23 of the switch are in contact with the arms 24, the chambers 100, 102 and 104 will be simultaneously opened to the atmosphere, whereupon the diaphragms 105, 107 and 109 will 130

be raised. The raising of the diaphragms 100 and 104 raises the valves 91 and 97, thereby cutting off communication of the chambers 81 and 87 with the atmospheric conduit 90 and opening up communication of said chambers with the suction conduit 80. The suctional force which is at this time communicated to the chamber 111 and the suctional force simultaneously communicated to the chamber 114 are balanced by the suctional force in the chambers 110 and 113 and consequently the diaphragms 112 and 115 remain inactive so that the valves 92 and 96 controlling the chambers 82 and 86 through which the adjusting pneumatics 135 and 136 for the lever or arm 132 are connected with the suction conduit remain closed. The raising of diaphragm 107 raises the valve 94 and places the pneumatic 130 under suction. This moves the lever or arm 132 longitudinally but while so moved it is in a neutral position. Consequently, neither of the pneumatics 43 or 44 are operated.

25 When, however, there is any variation between the times of registration of any one of the tempo-apertures with the aperture 22 of the tracker board and the closing of the circuit through the magnet 27, the forces 30 on opposite sides of the diaphragm 112 or the diaphragm 115 will become unbalanced and one or the other of the pneumatics 135 and 136 will be placed under suction, according to whether the registration of the 35 perforation 20 with the aperture 22 is ahead of or follows the closing of the circuit through the magnet:

Thus, if the record is moving faster than the film so that its opening 20 will register 40 with the aperture 22 before the closing of the circuit through the magnet, the opening of the chamber 100 to the atmosphere and the raising of the valve 91 and consequent putting of the chamber 111 under suction, occurs before the chamber 110 is 45 also placed under suction. Hence, the forces on opposite sides of the diaphragm 112 are unbalanced, the predominating force being effective to raise the diaphragm 112 and through it the valve 92. The valve 92 is thus caused to cut off communication of the chamber 82 with the atmospheric conduit 90 and open communication of said chamber with the suction conduit 80. The pneumatic 135 is now in communication with the suction conduit 80 through the duct 139, chamber 82 and port 82^b and is collapsed, thereby moving the arm or lever 132 toward the right into position wherein upon its downward movement it will act upon the valve 141. This downward movement of the arm or lever 132, it will be remembered, is caused by the collapsing of the pneumatic 130 but until 60 the circuit through the magnet 27 is closed and the chamber 104 is thereby opened to the atmosphere, the chamber 117 is under atmospheric pressure through the duct 126, chamber 87 and port 87^a and the valve 94 remains seated and prevents collapsing of the pneumatic 130. Assuming now that the lever has been adjusted toward the right and that the circuit through the magnet has been closed, the pneumatic 130 will be collapsed and will cause the lever or arm 132 to move the valve 141 away from its seat, thereby opening the chamber 103 to the atmosphere. The diaphragm 108 will now be raised and will raise the valve 95 thereby opening the chamber 85 to the suction conduit and causing the pneumatic 43 to be placed under suction communicated thereto through the duct 147, chamber 85 and port 85^b. The pneumatic 43 being thus collapsed will cause its arm 41 to turn the ratchet 40 one tooth. This turns the shaft 39, and causes the gear 38, oscillatory member 35 and valve stem 34 to move the valve 33 toward the right, thereby reducing the area of the opening 31 through which the motor C receives the suctional force by which it is operated. This operation is repeated until the movements of the record and shaft E are synchronized, it being understood that the valves 123 and 141 are self-closing and that when the chambers 100, 102, 103 and 104 are shut off from communication with the atmosphere (which occurs as soon as the particular tempo-perforation 20 through which the chambers 100 and 102 are open to the atmosphere is passed out of registration with the aperture 22 in the tracker board and the magnet has been deenergized by the passage of the conducting portions 23 of the switch out of engagement with the arms 25) the valves 91, 92, 94, 95 and 97 will return to their former positions in which the chambers 81, 82, 84, 85 and 87 are open to the atmosphere through the ports 81^a, 82^a, 84^a, 85^a and 87^a and the conduit 90, thereby permitting the pneumatics 135, 130 and 43 to return to their expanded conditions ready for another operation.

On the other hand, when the film is moving faster than the record, so that the circuit is closed by the second controlling element before the corresponding tempo-perforation 20 in the first controlling element comes into registration with the aperture 22, the chamber 104 will be opened to the atmosphere before the chambers 102 and 100 and the valve 97 will be raised before the valves 94 and 91 with the following result:

The chamber 114 will be in communication with the suction conduit 80, through the channel 127, chamber 87 and port 87^b while the chamber 113 is still under atmospheric pressure. Hence, the diaphragm 115 will be raised, thereby raising the valve 96 and 65 125

establishing communication of the pneumatic 136 with the suction conduit 80. This pneumatic being thus collapsed moves the lever or arm 132 to the left into line with the valve 142, so that when the pneumatic 136 is collapsed the valve 142 will be forced from its seat. The raising of the valve 97 also establishes communication of the chamber 117 with the suction conduit so that the suctional forces on opposite sides of the diaphragms 118 are now balanced, and the raising of said valve 97 further establishes communication of the chamber 110 with the suctional conduit so as to hold the valve 92 fast upon the seat controlling communication of the chamber 82 with the suction conduit 80. It will thus be apparent that when the chambers 100, 102 are opened to the atmosphere by the passage of a tempo-perforation 20 of the first controlling element over the aperture 22 of the tracker board, the suctional forces acting upon the diaphragms 107 and 118 in an upward direction will overcome the suctional force acting upon said diaphragm 118 in a downward direction and consequently the valve 94 will be raised and communication of the pneumatic 136 with the suctional conduit 80 established, thus moving the lever or arm 132 longitudinally and causing it to press the valve 142 away from its seat. The opening of the chamber 100 to the atmosphere causes the valve 91 to be raised and places the chamber 111 in communication with the suction conduit 80, but as the chamber 110 is also under suction, the suctional forces on opposite sides of the diaphragm 112 balance each other and the valve 92 is not opened until the valve 97 is closed. Meanwhile, the opening of the chamber 101 to the atmosphere causes the valve 93 to be raised thereby opening the chamber 83 to the suctional conduit 80. This causes the pneumatic 44 to be placed under suction through the duct 148, chamber 83 and duct 33, whereupon it is moved and caused through its described connection with the valve 33 to move the latter so as to increase the area of the opening 31 and cause the motor C to run faster.

I have thus illustrated and described in detail what I consider to be the most practical embodiment of my invention but I would have it understood that this particular embodiment of the invention is merely exemplary and that changes may be made and the invention otherwise and variously embodied without departing from its spirit or the scope of the subjoined claims.

Having now described the invention what I believe to be new and desire to secure by Letters Patent, is:—

1. Mechanism for synchronizing the operation of moving parts including, in combination, a motor for one of the said parts

selecting means controlled by that moving part which is in advance of the other, and means rendered effective under control of the other moving part for controlling the strength of the force exerted upon the motor to accelerate or retard the speed of the latter as predetermined by the operation of the selecting means. 70

2. Mechanism for synchronizing the operation of moving parts comprising, in combination, a motor for one of said parts and elements for controlling the strength of the force exerted upon the motor, including means settable to determine whether the speed of the motor shall be increased or retarded and connections for setting said means under control of that moving part which is in advance of the other. 75 80

3. Mechanism for synchronizing the operation of moving parts comprising, in combination, a motor for one of the said parts, and mechanism for controlling the strength of the force exerted upon the motor including a member settable into position to effect, when actuated, an increase or decrease in 90 the speed of the motor, means under control of that moving part which is in advance of the other for setting said member, and means rendered effective under control of the other moving part to actuate said 95 member. 85

4. Mechanism for synchronizing the operation of moving parts comprising, in combination, a motor for one of said parts, devices, connection through which the strength 100 of the force exerted upon the motor is controlled to diminish the speed of the motor when one device is operated and accelerate the speed of the motor when the other device is operated, and means for operating said 105 devices, said means including a settable member, elements for setting the member into operable position with respect to one or the other of said devices respectively, under control of that moving part which is in advance of the other, and elements rendered effective under control of the other moving part for causing said member to operate 110 the device for which it has been set. 110

5. Mechanism for synchronizing the operation of moving parts, comprising in combination, a motor for one of said parts, a pair of elements and connections between said elements and the motor controlling the strength of the force exerted upon the motor to effect an increase or decrease in the speed of the motor according to which of 115 said elements is actuated, an actuator for said elements, means acting under control of one or the other of the moving parts to 120 be synchronized for moving the actuator to position to engage one or the other of said elements according to which of the moving parts is in advance of the other and means rendered effective under control of the other 125 130

moving part to move said actuator to operate said element.

6. Mechanism for synchronizing the operation of moving parts, comprising, in combination, a motor for driving one of the parts to be synchronized, primary controllers operable in accord with the movements of said parts, respectively and connections to the motor, said connections being controlled by the primary controllers and including separate valves operable to effect an acceleration or retardation of the speed of the motor, respectively, and also including means by which only that valve which is controlled by the primary controller traveling in advance of the other primary controller is opened in changing the speed of the motor.

7. Mechanism for synchronizing the operation of moving parts, comprising, in combination, a motor for driving one of the parts to be synchronized, primary controllers operable in accord with the movements of said parts, respectively, and connections between the primary controllers and the motor, said connections including separate valves which are operable to effect an acceleration or retardation of the speed of the motor, respectively, and also including additional valves which respectively control the first mentioned valves and in turn are controlled by the primary controllers, respectively, and means for opening the additional valve which is controlled by the primary controller traveling in advance of the other primary controller.

8. Mechanism for synchronizing the operation of moving parts, comprising, in combination, a motor for driving one of the parts to be synchronized, primary valves, means for opening the primary valves in accord with the movements of the parts to be synchronized, secondary valves, connections between the secondary valves and the motor, through which the speed of the motor is increased when one secondary valve is opened and reduced when the other secondary valve is opened, additional valves respectively controlling the secondary valves, and means controlled by the primary valves and in turn controlling the additional valves to open one additional valve when one primary valve is opened in advance of the other and to open the other additional valve when the other primary valve is opened first.

9. Mechanism for synchronizing the operation of moving parts, comprising, in combination, a motor for driving one of the parts, primary valves, means for operating the primary valves in accord with the movements of the parts to be synchronized, respectively, secondary valves, connections between the secondary valves and the motor for accelerating or retarding the speed of the motor according to which valve is

opened, and connections between the primary valves and the secondary valves, the latter connections including valves and means for selectively operating the same under control of the primary valves to selectively control the secondary valves.

10. Mechanism for synchronizing the operation of moving parts, comprising, in combination, a motor for driving one of the parts, primary valves, means for operating said valves in accord with the movements of the parts to be synchronized, respectively, secondary valves, connections between the secondary valves and the motor, and connections between the primary valves and the secondary valves, including atmospheric ducts, valves for controlling said ducts and means to selectively open the last named valves under control of the primary valves.

11. Mechanism for synchronizing the operation of moving parts, comprising, in combination, a motor for one of the parts to be synchronized, and means for effecting an increase or decrease in the speed of the motor comprising a pair of valves, means under control of the moving parts for determining which of the valves is to be actuated, and actuating means for said valves also under control of the moving parts.

12. Mechanism for synchronizing the operation of moving parts, comprising in combination, a motor for one of said parts, a pair of air-controlling valves, pneumatically operable means controlled by said valves respectively, means by which the pneumatically-operable means control the strength of the force exerted upon the motor to effect an increase or decrease in the speed of the motor according to which of the air-controlling valves is opened, an actuator for said valves means acting under control of one or the other of the moving parts to be synchronized for moving the actuator to position to engage one or the other of said valves according to which of the moving parts is in advance of the other, and means rendered effective under control of the other moving part to move said actuator to open said valve.

13. Mechanism for synchronizing the operation of moving parts comprising, in combination, a motor for one of said parts, a pair of valves the movements of which effect an increase or decrease in the speed of the motor according to which of said valves is actuated, actuating means for said valves adjustable into and out of operating position with respect to said valves and pneumatic means for adjusting and actuating said actuating means.

14. Mechanism for synchronizing the operations of moving parts comprising, in combination, a motor for one of said parts, a valve, connection between said valve and the motor, an actuator for said valve, movable

to and from operative position with respect to the valve, a pneumatic for adjusting the actuator and a pneumatic for bodily moving the actuator to open the valve.

- 5 15. Mechanism for synchronizing the operations of moving parts, comprising a pneumatic motor for one of the parts, a governor valve having connection with said motor, and a mechanism for moving the governor valve to vary the speed of the motor to accord with the speed of the other part, said mechanism including a pair of pneumatics, an oscillatory member having connection with the valve, and means operated 70
- 16 by the pneumatics for moving the oscillatory member in opposite directions, respectively.

16. Mechanism for synchronizing the operation of moving parts, comprising, in combination, a motor for one of said parts, a 75
- 20 pair of primary controlling valves, means by which the primary controlling valves are controlled by the moving parts respectively, a pneumatically adjustable and actuatable operating element, devices whereby 80
- 25 the pneumatic forces controlling said element are controlled in accordance with the movements of the primary controlling valves, and pressure controlling means actuated under control of said element and in 85
- 30 turn controlling the pressures to the motor.

17. Mechanism for synchronizing the operation of moving parts comprising, in combination, a motor for one of said parts, a pair of primary controlling valves, means 90
- 35 by which the primary controlling valves are controlled by the moving parts respectively, and connections between the primary controlling valves and the motor; said connections comprising a pneumatically controlled 95
- 40 and actuated element and elements whereby the pneumatic forces controlling the first mentioned element are in turn controlled in accordance with the movements of the primary controlling valves, including means
- 45 to set said first mentioned element into position to effect when it is actuated, an increase or decrease in the speed of the motor, according to which of said valves is opened first, and also including means whereby said first 100
- 50 mentioned valve is actuated when the other primary valve is opened.

18. Mechanism for synchronizing the operation of moving parts comprising, in combination, a motor for one of said parts and 105
- 55 means for selectively controlling the forces which operate said motor to increase or reduce the speed thereof, including a pair of primary controllers, a pair of valves, means whereby said valves control the effective 110
- 60 strength of the force which operates the motor and elements for opening said valves selectively including an adjusting means operated under control of the primary controller associated with the moving part traveling in advance of the other and an op-

erating means under the combined or conjoint control of the primary controllers.

19. Mechanism for synchronizing the operation of moving parts comprising, in combination, a motor for one of the parts and devices for increasing or reducing the speed of the motor including means selectively operated under control of that part which is in advance of the other for determining whether the strength of the operating force effective upon the motor shall be increased or reduced and means operated under the conjoint control of the moving parts for controlling said force to increase or reduce the speed of the motor as predetermined by 80
- 75 the operation of the first named means.

20. Mechanism for synchronizing the operation of moving parts comprising, in combination, a motor for one of the parts, a pair of primary controllers operable in accord 85
- 25 with the moving parts respectively, a pair of primary valves respectively controlled by said controllers, means under control of the respective primary valves and operated under control of the primary valve opened 90
- 30 first, to determine whether the operating force effective upon the motor shall be increased or reduced, and means under the conjoint control of the primary controllers and operated when the other primary valve 95
- 35 has been opened, for controlling said force to increase or reduce the speed of the motor as predetermined by the operation of the first named means.

21. Mechanism for synchronizing the operation of moving parts comprising, in combination, a motor for one of the parts, a pair of primary controllers operable in accord with the moving parts respectively, a pair of primary valves respectively controlled by said controllers, a pair of secondary valves, connections between the secondary valves and the motor and connections between the primary valves and the secondary 100
- 40 valves including means operated under control of the primary valves respectively, to determine which secondary valve shall be opened and means under the conjoint control of the primary controllers to cause one or the other secondary valve to be 105
- 45 opened as predetermined by the operation of the first named means.

22. Mechanism for synchronizing the operation of moving parts comprising, in combination, a motor for one of the parts, a pair of primary valves, means for opening the same in accord with the movements of the parts to be synchronized respectively, a pair of pressure operated secondary valves, connections between the secondary valves and the motor, for speeding up the motor when one valve is opened and slowing it down when the other valve is opened, and means for opening the secondary valves selectively, including pressure controlling means for 110
- 50

- the secondary valves, an adjustable actuating element therefor, and means for adjusting the actuating element into operative relation with the pressure controlling means 5 of one or the other secondary valve under control of the first opened primary valve and for actuating it to operate the pressure controlling means when the second opened primary valve is opened.
- 10 23. Mechanism for synchronizing the operation of moving parts comprising, in combination, a motor for one of the parts, a pair of primary valves, means for opening the same in accord with the movements of the 15 parts to be synchronized, respectively, a pair of pressure operated secondary valves, connections between the secondary valves and the motor for speeding up the motor when one valve is opened and slowing it 20 down when the other valve is opened, and means for opening the secondary valves selectively, including pressure controlling valves for the secondary valves, respectively, an adjustable actuating arm for the pressure 25 controlling valves, means for adjusting said arm into operative relation with one or the other of said valves under control of the primary valve first opened, and means for operating said arm to open the valve 30 for which it has been set when the other primary valve has been opened.
24. Mechanism for synchronizing the operation of moving parts comprising, in combination, a motor for one of the parts, a pair 35 of primary valves, means for opening the same in accord with the movements of the parts to be synchronized, a pair of pressure operated secondary valves, connections between the secondary valves and the motor 40 for speeding up the motor when one valve is opened and slowing it down when the other valve is opened, and means for opening the secondary valves selectively, including pressure controlling valves for the secondary 45 valves, respectively, an adjustable actuating arm for the pressure controlling valves, adjusting pneumatics for the arm, an actuating pneumatic for the arm, connections between the adjusting pneumatics and the primary 50 valves for operating them under control of said valves respectively and means for operating the operating pneumatic when both primary valves have been opened.
25. Mechanism for synchronizing the operation of moving parts comprising, in combination, a motor for one of the parts, a pair of primary valves, means for opening the same in accord with the movements of the parts to be synchronized, a pair of pressure 55 controlled secondary valves, connections between the secondary valves and the motor, for speeding up the motor when one valve is opened and slowing it down when the other valve is opened, and means for opening the 60 secondary valves selectively, including pressure controlling valves for the secondary valves, respectively, an adjustable actuating arm for the pressure controlling valves, adjusting pneumatics for the arm, an actuating pneumatic for the arm, connections between the adjusting pneumatics and the primary valves for operating them under control of said valves respectively and means for operating the operating pneumatic when both primary valves have been opened.
26. Mechanism for synchronizing the operation of moving parts comprising, in combination, a motor for one of said parts, a pair of valves, means under control of said valves for effecting an increase or decrease 65 in the speed of said motor according to which of said valves is actuated, and mechanism under control of the moving parts, for opening said valves and including means under control of that moving part which is 70 in advance for holding the valve associated with the other moving part, closed.
27. Mechanism for synchronizing the operation of moving parts comprising, in combination, a motor for one of said parts, a pair 75 of pneumatically-operable valves, means under control of said valves for varying the speed of the motor and means under control of the moving parts for controlling the pneumatic forces to said valves to open one or 80 the other, according to which part is traveling faster than the other, including elements by which when either valve is opened the other is locked in closed position during 85 the period corresponding to the difference 90 in the speeds of the moving parts.
28. Mechanism for synchronizing the operation of moving parts comprising, in combination, a motor for one of said parts, a pair 95 of pneumatically-operable valves, means under control of said valves for varying the speed of the motor and means under control of the moving parts for controlling the pneumatic forces to said valves to open one or 100 the other, according to which part is traveling faster than the other, including elements by which when either valve is opened the other is locked in closed position during 105 the period corresponding to the difference 110 in the speeds of the moving parts.
29. Mechanism for synchronizing the operation of moving parts comprising, in combination, a motor for one of said parts, a pair 115 of pressure operated valves, means between the said valves and the motor for in- 120

creasing or reducing the strength of the forces exerted upon the motor according to which of the valves is opened, and means for opening said valves under control of the moving parts, including a pair of primary valves, and connections between each primary valve and both of the first mentioned valves through which the latter are subjected to pressures varied under the control of the primary valves, to open one of the first mentioned valves and lock the other when the corresponding primary valve is opened in advance of the other primary valve, and cause a counterbalancing of the pressure on each of said first mentioned valves when both primary valves are opened at the same instant.

30. Mechanism for synchronizing the operation of moving parts comprising, in combination, a motor for one of said parts, a pair of primary valves, a pair of secondary valves, connections between the secondary valves and the motor operable to increase or decrease the strength of the force effective upon the motor according to which secondary valve is opened, and connections between the primary valves and the secondary valves, including pressure operated members having a third pair of valves connected thereto and connections between each of said pressure operated members and both of said primary valves, whereby the secondary valves are opened under control of the primary valves respectively through the medium of the third pair of valves and said third pair of valves are so correlated with the primary valves that one of the third pair of valves is opened and the other locked in closed position when one primary valve is opened and is closed and the locked valve released when the other primary valve has been opened.

31. Mechanism for synchronizing the operation of moving parts comprising, in combination, a motor for one of said parts and means for changing the speed of the motor under control of the moving parts including a pair of pressure-operable valves which are opened to increase and reduce the speed of the motor, respectively, and inter-related means for controlling the pressures to said valves to cause one or the other valve to be opened under control of the moving part which is traveling faster than the other and to be closed under control of said other moving part and neither of said valves to be opened when the parts are traveling at the same speed.

32. Mechanism for synchronizing the operation of moving parts comprising, in combination, a motor, pressure-controlling means therefor, an actuating element for the pressure controlling means, a pneumatically operable means for moving said element, a valve for controlling the pressure

to said pneumatically operable means, pressure operated means connected with the valve, means under control of one moving part for periodically supplying pressure to the said pressure operated means tending to open the valve and, means by which an opposing pressure is imposed on the pressure operable means, and is varied under control of the other moving part. 70

33. Mechanism for synchronizing the operation of moving parts comprising, in combination, a motor, pressure controlling means having elements through which the speed of the motor is accelerated and retarded respectively, an adjustable actuating element for the pressure controlling means, means for adjusting said element into position to act upon the pressure controlling means to accelerate or retard the speed of the motor as required when the moving parts are not traveling in their proper timed relation and means for moving said element to operate the pressure controlling means when it has been thus adjusted. 75 80

34. Mechanism for synchronizing the operation of moving parts, comprising, in combination, a motor, pressure controlling means having elements through which the speed of the motor is accelerated and retarded, respectively, an adjustable actuating element for the pressure controlling means, means for adjusting said element under control of one moving part into position to act upon the pressure controlling means to accelerate or retard the speed of the motor when the moving parts are not traveling in their proper timed relation, and means under control of the other moving parts for moving said element to operate the pressure controlling means when it has been thus adjusted. 85 90 95

35. Mechanism for synchronizing the operation of moving parts comprising, in combination, a motor for one of said parts and means under control of the moving parts for controlling the speed of the motor, including selecting and actuating means having a pneumatically operable element and devices for controlling the pneumatic forces to said element said devices comprising a valve, a pair of pressure-operated diaphragms connected to the valve, means through which one side of each diaphragm is constantly exposed to air of the same pressure, and means for varying the pressure on the other sides of the diaphragms under control of the moving parts, respectively, to open said valve when both moving parts have attained a predetermined relation. 100 110 115

36. Mechanism for synchronizing the operation of moving parts comprising, in combination, a motor for one of said parts and means under control of the moving parts for controlling the speed of the motor, including mechanism of a selective nature 120 125 130

- having a pressure controlling means, an actuating element therefor, a pneumatic for operating said element and connections for controlling the pneumatic, said connections 5 having a valve, a pair of diaphragms on opposite sides of the valve, one side of each being exposed to air of an equal pressure, and means for varying the pressure on the other side of the diaphragms under control 10 of the moving parts respectively, to open said valve when both moving parts have attained a predetermined relation.
37. Mechanism for synchronizing the operation of moving parts comprising, in combination, a motor for one of said parts, a pair of valves, connections between said valves and the motor for increasing or decreasing the speed of the motor under control of the valves, respectively, pressure controlling means for the valves respectively, and means for controlling said pressure controlling means including an actuating element, a pneumatic for operating the same, a valve for controlling the air to the interior 20 of the pneumatic, a pair of diaphragms on opposite sides of the valve, means through which the sides of the diaphragms presented toward said valve are constantly exposed to the same pressure, means through which the 25 other side of one diaphragm is intermittently subjected to a different pressure under control of one moving part, and means through which the other side of the other diaphragm is alternately exposed to the 30 air of different pressures under control of the other moving part.
38. Mechanism for synchronizing the operation of moving parts comprising, in combination, a motor for one of said parts, a pair of primary controllers operable in accord with the moving parts, respectively, a pair of valves, connections between said valves and the motor for increasing or reducing the speed of the motor under control 35 of the valves, respectively, pressure controlling means for the valves, respectively, and means for controlling said pressure controlling means including an actuating element, a pneumatic for operating the same, a valve for controlling the air to the interior 40 of the pneumatic, a pair of diaphragms on opposite sides of the valve, means through which the sides of the diaphragms presented toward said valve are constantly exposed to the same pressure, means through which the other side of one diaphragm is intermittently subjected to a different pressure, under control of one of the primary controllers, a duct for air of different pressures 45 leading to the other side of the other diaphragm, a valve for controlling said duct, and means whereby the last named valve is operated under control of the other primary controller.
39. Mechanism for synchronizing the 50 operation of moving parts comprising, in combination, a motor for one of said parts, a pair of primary controllers operable in accord with the moving parts, respectively, a pair of valves, connections between said valves and the motor for increasing or reducing the speed of the motor under control of the valves, respectively, pressure controlling means for the valves, respectively, and means for controlling said pressure controlling means including an actuating element, means controlled by the primary valves for adjusting said actuating element into operative relation with a pressure controlling means for the secondary valves, respectively, an operating pneumatic for said actuating element, a valve for controlling the air to the interior of said pneumatic, a pair of diaphragms on opposite sides of the valve, means through which the sides of the diaphragms presented toward said valve are constantly exposed to the same pressure, means through which the other side of one diaphragm is intermittently subjected to a different pressure under control of one of the primary controllers, and a duct for air of different pressures leading to the other side of the other diaphragm, said duct being controlled by the primary valve associated with the other primary controller.
40. In a mechanism for synchronizing the operation of moving parts, the combination, with a motor and means for selectively varying the strength of the forces exerted upon the motor, including a pneumatic and the following instrumentalities, to wit: a chamber having communication with said pneumatic and with air sources of different pressures, a valve for controlling such communication, membranes on opposite sides of the valve and connected thereto, one surface of each membrane being constantly exposed to one of said sources of pressure, means operated under control of one of the parts to be synchronized for periodically opening communication of one of said sources with the other side of one membrane and means periodically operated under control of the other of the parts to be synchronized for opening communication of one or the other of said sources with the other side of the other membrane.
41. Mechanism for synchronizing the operation of moving parts, comprising, in combination, a motor for one of said parts, a selecting and actuating element, means controlled by said element for controlling the effective strength of the forces exerted upon the motor, and means for pneumatically adjusting said element into selecting position including a pair of pneumatics, connections between said pneumatics and element and

means for controlling said pneumatics from the moving parts respectively.

42. Mechanism for synchronizing the operation of moving parts comprising, in combination, a motor for one of said parts, a selecting and actuating element, means controlled by said element for controlling the effective strength of the forces exerted upon the motor and means for pneumatically operating said element including a pair of adjusting pneumatics and an operating pneumatic each connected thereto, means by which the adjusting pneumatics are severally controlled from the moving parts, respectively, and means by which the operating pneumatic is operated under the joint control of both moving parts.

43. In the mechanism for synchronizing the operation of moving parts, a selecting means comprising a movable element, means for shifting said element into selecting position under control of the moving part which is in advance, means rendered effective under control of the other moving part for actuating said element, a governor mechanism connected to the motor and means for controlling the governor mechanism under control of said element.

44. Mechanism for synchronizing the operation of moving parts comprising, in combination, a motor for one of said parts, a source of power for the motor, a governor mechanism for controlling the action of the source of power upon the motor and means for selectively controlling the governor mechanism including means moved to selecting position under control of that moving part which is in advance of the other and means for operating the same after it has been moved to selecting position rendered effective under control of the other moving part.

45. Mechanism for synchronizing the operations of moving parts, comprising, in combination, a motor for one of said parts, a plurality of primary controlling valves, and means including separate elements between said valves respectively and the motor, said elements being operable independently of each other to increase or decrease the effective strength of the forces exerted upon the motor according to which of said valves is actuated first.

46. Mechanism for synchronizing the operations of moving parts comprising a first controller and a second controller movable in accord with the parts to be synchronized, respectively, a governor valve, connections between the governor valve and one of said parts, pneumatically operated means for moving the governor valve, mechanism for selectively controlling the pneumatic forces to said valve-moving means, pneumatically operable valves for governing the action of

the selecting mechanism and means whereby the operations of the latter valves are severally controlled by the controllers.

47. Mechanism for synchronizing the operations of moving parts comprising a first controller and a second controller movable in accord with the parts to be synchronized, respectively, a governor valve, connections between the governor valve and one of said parts, pneumatically operated means for moving the governor valve, primary valves arranged to be severally controlled by the controllers, secondary valves for controlling the governor-valve moving means, and means for opening the secondary valves selectively according to which primary valve is opened first.

48. Mechanism for synchronizing the operations of moving parts, comprising, in combination, a driving motor for one of said parts, and means for automatically varying the speed of the motor to accord with the speed of the other part, said means including a governor valve connected with the motor, pneumatics connected with the governor-valve to shift the same in opposite directions, respectively, a first controller and a second controller movable in accord with the parts to be synchronized, respectively, primary valves severally controlled by the controllers, secondary valves, ducts connected with said pneumatics and controlled by the secondary valves, respectively, and means for opening the secondary valves selectively according to which primary valve is opened first.

49. Mechanism for synchronizing the operations of moving parts, comprising, in combination, a driving motor for one of said parts, and means for automatically varying the speed of the motor to accord with the speed of the other part, said means including a governor valve connected with the motor, pneumatics connected with the governor-valve to shift the same in opposite directions, respectively, a first controller and a second controller movable in accord with the parts to be synchronized, respectively, primary valves severally controlled by the controllers, pneumatically operable secondary valves, ducts connected with said pneumatics and controlled by the secondary valves, respectively, and mechanism for selectively controlling the secondary valves, including pneumatically-operable valves which are controlled by the primary valves.

50. Mechanism for synchronizing the operation of moving parts comprising a first controller and a second controller movable in accord with the parts to be synchronized, respectively, a governor valve, a pneumatically-operated means for moving governor valve, mechanism for selectively controlling the pneumatic force to the valve-moving

means, including a pneumatically operated part, connections to the valve-moving means controlled by said part, and pneumatically operated valves controlling the operation of 5 said pneumatically operated part, said valves in turn being controlled by the first and second controllers.

51. Mechanism for synchronizing the operation of moving parts comprising in combination 10 a first controller, a second controller, a governor valve, a pneumatically operated mechanism for moving said governor valve, ducts connected to said valve-moving mechanism, and means for controlling said ducts, said means including valves, a pneumatically operated operating element for said valves, pneumatically operated valves and means controlled by the latter valves and in turn controlling said element, 15 said latter valves being controlled by the first and second controllers.

52. Mechanism for synchronizing the operation of moving parts comprising in combination, a first controller, a second controller, 20 a governor valve controlling one of said parts, a pneumatically operated mechanism for moving said governor valve, ducts for said valve-moving mechanism, means for controlling said ducts, said means including 25 valves, a pneumatically operated valve-operating element movable to engage one or the other of said valves, and pneumatically actuated elements for operating said valve-actuating element to determine which of said 30 valves is to be engaged by it, and pneumatic valves for controlling the elements which move the valve-operating element, said valves in turn being controlled by the first and second controllers.

53. Mechanism for synchronizing the operation of moving parts comprising, in combination, a first controller, a second controller, a governor valve controlling one of said parts, a pneumatically operated mechanism 45 for moving said governor valve, control ducts for said valve moving mechanism, means for controlling said ducts, said means including valves, a bodily movable member adapted to be shifted to a position to engage 50 and operate one or the other of said valves, and means for shifting said member and for moving it bodily into engagement with one or the other of the valves under control of the first and second controllers.

54. Mechanism for synchronizing the operation of moving parts comprising a first controller, a second controller, a governor valve controlling one of said parts, a pneumatically operated mechanism for moving 60 said governor valve, ducts for said valve-moving mechanism, a bodily movable element, controlling means for the ducts, controlled by said element, and means, controlled by the first and second controllers,

for shifting the position of said element to 65 determine which duct is to be affected by its movement.

55. Mechanism for synchronizing the operation of moving parts comprising, in combination, a pneumatic motor for one of said parts, a valve for controlling the operation of the motor, a pneumatically operated means for moving the valve, and means for controlling said valve-moving means, the controlling means including conductors of 70 air of different pressures having connection with the valve-moving means, valved means for controlling the respective conductors, a movable actuating means for controlling the operations of the last named means, a first 75 controller, a second controller, and means whereby the movable actuating means is controlled by the first controller and second controller.

56. Mechanism for synchronizing the operation of moving parts comprising, in combination, a pneumatic motor for one of said parts, a valve for controlling the operation of the motor, a pneumatically operated means for moving the valve, and means for 80 controlling the valve-moving means, the controlling means including conductors of air of different pressures having connection with the valve-moving means, valved means for controlling the respective conductors, a 85 longitudinally movable laterally shiftable member for controlling the valved means, and means for shifting and operating said member automatically.

57. Mechanism for synchronizing the operation of moving parts, comprising, in combination, a pair of independently-operable pneumatics, a fluid-operated driving means for one of the moving parts, a governor-valve for controlling the speed thereof, a 100 stem for said valve, connections between the stem and the pneumatics, said connections including separate and independently operable elements connected to the respective pneumatics, and means for controlling the 105 pneumatics, including separate air conductors connected thereto, valves for the respective air conductors, pressure operated actuating members for the respective valves, valves controlling the operations of said 110 members, and an adjustable means for operating either of the last named valves.

58. In a mechanism for synchronizing the operation of moving parts, a motor for one of said parts, a governor valve, pneumatics 115 for shifting said valve to effect an increase or decrease in the speed of the motor, primary valves under the control of the moving parts respectively, secondary valves controlling the pneumatic forces to the pneumatics, and means for selectively controlling the secondary valves including additional valves, diaphragms connected to the 120 125

- additional valves, respectively, connections, each for air of different pressures, controlled by one primary valve and through which one side of one diaphragm and the other side of the other diaphragm are simultaneously subjected to similar pressures, connections each for air of different pressures, controlled by the other primary valve and through which the other sides of the diaphragms are simultaneously exposed to similar pressure, and means by which one or the other secondary valve is opened when the corresponding additional valve has been opened.
- 15 59. Mechanism for synchronizing the operations of moving parts, comprising, in combination, a fluid-operated driving motor for one of said parts, a governor valve for the motor, and means for automatically operating the governor valve to vary the speed of the motor to accord with the speed of the other part, said means including pressure-operated elements, controlling elements operated in accord with the movements of the parts to be synchronized, respectively, connections between the controlling elements and the pressure operated elements whereby the latter are operated selectively and only when the parts are moving out of synchronization with each other, and connections between the pressure-operated elements and the governor-valve so arranged that the operation of one pressure-operated element moves the valve in one direction and the operation of the other pressure-operated element moves the valve in the other direction.
60. Mechanism for synchronizing the operation of moving parts, comprising a pair of independently operable pneumatics, a fluid-operated driving means for one of said moving parts, a governor valve movable to vary the speed thereof to accord with the speed of the other part, adjusting connections between said valve and the pneumatics and means for operating said pneumatics independently of each other.
61. Mechanism for synchronizing the operation of moving parts, comprising a pair of independently operable pneumatics, a fluid-operated driving means for one of the moving parts, a governor-valve movable to vary the speed thereof to accord with the speed of the other part, an actuating element for said valve, means connecting the actuating elements with the pneumatics, said means including separate and independently operable elements connected to the respective pneumatics, and means for operating the pneumatics.
62. Mechanism for synchronizing the operations of moving parts, comprising a pneumatic motor for one of the parts, a governor valve having connections with said motor, and means for moving the governor valve to vary the speed of the motor to accord with

the speed of the other part, including a pair of independently operable pneumatics, an oscillatory member having connection with the valve and provided with arcual teeth, a shaft having a gear engaging said teeth and also having ratchets, and pawls connected to the respective pneumatics for engaging said ratchets.

63. Mechanism for synchronizing the operations of moving parts comprising, in combination with the parts to be synchronized, a pneumatic motor for one of said parts, a valve movable to vary the speed of the motor to accord with the speed of the other part and an operating means for the valve including a pair of independently operable pneumatics, means for operating the pneumatics independently of each other, a pivoted member having connection with the valve, and connections between the pivoted member and the pneumatics, the said connections, including pawls which are operated by the respective pneumatics, ratchets respectively engaged by the pawls and gearing connecting the ratchets with the pivoted member for operating the latter.

64. Mechanism for synchronizing the operation of moving parts, comprising a pair of independently operable pneumatics, driving means for one of said moving parts, a valve movable to vary the speed thereof to accord with the speed of the other part, connections between said valve and pneumatics independently of each other and means for operating said pneumatics, comprising chambers having openings through which they may have communication with air sources of different pressures and also having valves for controlling such communication, connections between said chambers and pneumatics, respectively, pressure-operated members respectively connected to said valves, and means arranged to control the operation of said pressure-operated members, including valves associated with said members respectively and operable to control the operation thereof, an operating element for said valves, and means for operating said element in accord with variations in the relative speeds of the moving parts whose movements are to be synchronized.

65. Mechanism for synchronizing the operation of moving parts, comprising a pair of pneumatics, a fluid-operated driving means for one of said moving parts, a governor valve for controlling the speed of the driving means, adjusting connections between said valve and the pneumatics and means for operating said pneumatics, comprising chambers having openings through which they may have communication with air sources of different pressures, and also having valves for controlling said communication, connections between said chambers

and pneumatics, respectively, and pressure-operated means arranged to control the operation of said valves in accord with variations in the relative speeds of the moving 5 parts which are to be synchronized comprising air-controlling means whereby the valves are each held in a certain position when the parts are moving in synchronism and one or the other of the valves is moved 10 when said parts are not synchronized.

66. Mechanism for synchronizing the operations of moving parts comprising a pair of pneumatics, a fluid-operated driving means for one of said moving parts, a governor-valve for controlling the speed of the 15 driving means, connections between said valve and the pneumatics and means for operating said pneumatics, comprising secondary valves, ducts connected to the pneumatics and controlled by the secondary valves, means including the primary valves for controlling the secondary valves, and controllers respectively movable in accord with the parts to be synchronized and controlling the primary valves respectively.

67. Mechanism for synchronizing the operations of moving parts comprising a pair of pneumatics, a fluid-operated driving means for one of said moving parts, a governor-valve for controlling the speed of the 30 driving means, connections between said valve and the pneumatics and means for operating said pneumatics, comprising primary valves, secondary valves, ducts for air 35 of different pressures, connected to the pneumatics and controlled by the secondary valves, controllers respectively movable in accord with the parts to be synchronized and arranged to control the primary valves, respectively, and means for selectively operating the secondary valves, said means including valves which are controlled from the primary valves.

68. Mechanism for synchronizing the operations of moving parts comprising a pair of pneumatics, a fluid-operated driving means for one of said moving parts, a governor-valve for controlling the speed of the driving means, connections between said 45 valve and the pneumatics and means for operating said pneumatics comprising primary valves, secondary valves, ducts for air of different pressures, connected to the pneumatics and controlled by the secondary 50 valves, controllers respectively movable in accord with the parts to be synchronized and arranged to control the primary valves, respectively, and means for selectively operating the secondary valves, said means including valves, an actuating element for the latter valves, connections between said latter valves and the secondary valves, respectively, adjusting pneumatics for the actuating element, valves for controlling said 60 pneumatics, connections between the pri-

mary valves and the last named valves, an operating pneumatic for the actuating element and means for controlling the latter pneumatic in accord with the primary valves.

69. Mechanism for synchronizing the operation of moving parts, comprising a fluid-operated driving means for one of the parts whose movements are to be synchronized, a governor valve operable to control the speed 70 thereof, a pair of pneumatics, connections between the valve and pneumatics, and means for operating said pneumatics, including chambers having connection with said pneumatics, respectively, and also having openings through which they may have communication with air sources of different pressures and valves for controlling said communication, a second pair of pneumatics, chambers having communication with the 75 latter pneumatics, respectively, the latter chambers also having openings through which they may have communication with sources of air of different pressures and valves for controlling such communication, 80 pressure operated means connected to the first-mentioned valves and means for varying the pressures on said pressure-operated means, including valves, movable operating means for said valves, and adjusting connections between said operating means and the second pair of pneumatics.

70. Mechanism for synchronizing the operation of moving parts, comprising a fluid-operated driving means for one of the parts 100 whose movements are to be synchronized, a governor valve operable to control the speed thereof, a pair of pneumatics, connections between the valve and the pneumatics, and means for operating said pneumatics including chambers having connection with said pneumatics, respectively, and also having openings through which they may have communication with air sources of different pressures and valves for controlling said 105 communication, pressure operated means connected to said valves, and means for varying the pressures on said pressure operated means in accordance with variations in the relative speeds of the parts whose movements are to be synchronized, including a second pair of pneumatics, chambers having communication with the latter pneumatics, respectively, the latter chambers also having 110 openings through which they may have communication with air sources of different pressures and valves for controlling such communication, means under control of the moving parts for operating the latter valves, adjusting elements connected to the second pair of pneumatics, an element adjusted thereby, means for moving the latter element after it has been adjusted, and valves 115 operated by said latter element.

71. Mechanism for synchronizing the op- 120

- eration of moving parts, comprising a fluid-operated driving means for one of the parts whose movements are to be synchronized, a governor valve operable to control the speed thereof, a pair of pneumatics, connections between the valve and pneumatics, and means for operating said pneumatics including chambers having connection with said pneumatics, respectively, and also having openings through which they may have communication with air sources of different pressures and valves for controlling said communication, pressure operated means connected to said valves, and means for varying the pressures on said pressure operated means comprising valves for controlling pressure thereto and means for operating said valves selectively, including a lever, a second pair of pneumatics, adjusting connections between said lever and the second pair of pneumatics to adjust the lever into line with one or the other valve when the proper pneumatic is operated, chambers having communication with the second pair of pneumatics, respectively, and also having openings through which they may have communication with sources of air of different pressures and valves for controlling said communication, pressure operated means connected to the last-mentioned valves, means to control the operation of the last-mentioned pressure operated means in accordance with variations in the relative speeds of the parts whose movements are to be synchronized, and means for pneumatically moving the lever into engagement with the respective valves when it has been adjusted by the operation of the second pair of pneumatics.
72. In a mechanism for synchronizing the operation of moving parts, a pair of chambers having openings through which they may have communication with air sources of different pressures, said chambers also having pressure-operable valves to control such communication, means including primary and selecting valves for controlling the pressures to the first named valves under control of variations in the relative speeds of the moving parts, and means whereby the speed of one of the moving parts will be changed in accordance with variations in the relative times of operations of said valves.
73. In a mechanism for synchronizing the operation of moving parts, a pair of chambers having openings through which they may have communication with air sources of different pressure, said chambers also having pressure-operable valves, means operable under control of variations in the relative speeds of the moving parts for controlling the operations of the pressure-operable valves, a second pair of chambers having openings through which they may

have communication with either source, valves for controlling such communication, means whereby the operations of said valves are controlled by the operations of the first valves, and connections between the second pair of chambers and one of the parts whose movements are to be synchronized with another. 70

74. In a mechanism for synchronizing the operation of moving parts, a pair of chambers having openings through which they may have communication with air sources of different pressures, pressure-operable valves to control such communication, means operable under control of variations in the relative speeds of the moving parts for controlling the operations of said valves, a second pair of chambers having openings through which they may have communication with either of said air sources, valves for controlling such communication, a third pair of chambers having openings through which they may have communication with either air sources, valves for controlling such communication, means whereby the operations of the last named valves are controlled by the operations of the first named valves, connections between the third pair of chambers and the valves of the second pair of chambers whereby the latter are operated under control of the valves of said third pair of chambers, and connections between the second pair of chambers and one of the parts whose movements are to be synchronized with another. 80

75. In a mechanism for synchronizing the operation of moving parts, a pair of chambers having openings through which they may have communication with air sources of different pressure, pressure-operable valves to control such communication, means operable under control of variations in the relative speeds of the moving parts for controlling the operations of said valves, a second pair of chambers having openings through which they may have communication with either of said air sources, valves for controlling such communication, a third pair of chambers having openings through which they may have communication with either of said air sources, valves for controlling such communication, means whereby the operations of the last named valves are controlled by the operations of the first named valves, pressure-operated means connected to the valves of the second pair of chambers, respectively, pneumatics having connection with the third pair of chambers respectively, means connected to said pneumatics for controlling the operations of the pressure-operated means of the valves in the second pair of chambers, and connections between the second pair of chambers and one of the parts whose movements are to be synchronized with another. 100

76. In a mechanism for synchronizing the operation of moving parts, a pair of chambers having openings through which they may have communication with air sources of different pressure, said chambers also having pressure-operable valves to control such communication, means operable under control of variations in the relative speeds of the moving parts for controlling the operations of said valves, a second pair of chambers having openings through which they may have communication with either of said air sources, valves for controlling such communication, a third pair of chambers having openings through which they may have communication with either of said air sources, valves for controlling such communication, means whereby the operations of the last named valves are controlled by the operations of the first named valves, pressure-operable means connected to the valves of the second pair of chambers, respectively, pneumatics having connection with the third pair of chambers respectively, a pivotally-adjustable lever, connections between said lever and pneumatics, means for moving said lever longitudinally, valves for controlling the pressures on the pressure-operated means for the valves of the second pair of chambers, arranged to be operated by said lever, and connections between the second pair of chambers and one of the parts whose movements are to be synchronized.
77. In a mechanism for synchronizing the operation of moving parts, a pair of chambers having openings through which they may have communication with air sources of different pressure, said chambers also having pressure-operable valves to control such communication, means operable under control of variations in the relative speeds of the moving parts for controlling the operations of said valves, a second pair of chambers having openings through which they may have communication with either of said air sources, valves for controlling such communication, a third pair of chambers having openings through which they may have communication with either of said air sources, valves for controlling such communication, means whereby the operations of the last named valves are controlled by the operations of the first named valves, pressure-operable means connected to the valves of the second pair of chambers, respectively, pneumatics having connection with the third pair of chambers respectively, a pivotally-adjustable lever, connections between said lever and pneumatics, a pneumatic connected to the lever for moving the same longitudinally, valves for controlling the operations of the pressure-operated means for the valves of the second pair of chambers, and connections between the second pair of chambers and one of the parts whose movements are to be synchronized.
78. In mechanism for synchronizing the operation of moving parts, a motor for one of said parts, a governor valve for the motor, pneumatics for actuating said valve, and means under control of the moving parts for actuating one or the other of said pneumatics according to which of said parts is moving in advance of the other, said means comprising elements acting under control of the part moving in advance of the other to determine which of the pneumatics is to be actuated and elements under control of the other part to actuate said pneumatic.
79. In a mechanism for synchronizing the operation of moving parts, a pair of chambers having openings through which they may have communication with air sources of different pressures, secondary valves for controlling such communication, connections between said chambers and one of the parts whose movements are to be synchronized with another, pressure-operated means having connection with said valves, and means controlled by variations in the relative speeds of the parts to be synchronized for controlling the operations of said pressure-operated means, said means including a system of primary and selecting valves arranged to cause one or the other of the secondary valves to be operated according to whether the part having connection with said chambers is moving too fast or too slow and to cause both of said valves to be not affected by movements of the moving parts when the latter are in synchronism with each other.
80. In a mechanism for synchronizing the operation of moving parts, a pair of chambers having openings through which they may have communication with air sources of different pressures, valves for controlling such communication, connections between said chambers and one of the parts whose movements are to be synchronized with another, pressure-operated means having connection with said valves, and means controlled by variations in the relative speeds of the parts to be synchronized for controlling the operations of said pressure-operated means, said means comprising a second pair of chambers having openings through which they may have communication with either of said air sources, valves in said second pair of chambers for controlling such communication, pressure-operated means connected to said valves, means operated in consonance with the movements of the parts to be synchronized for controlling the operation of the pressure operated means of the valves in the second pair of chambers, and means whereby the non-simultaneous operation of the last named valves causes one or the other of the first-named valves to be moved.

81. In a mechanism for synchronizing the operation of moving parts, a pair of chambers having openings through which they may have communication with air sources of different pressures, valves for controlling such communication, connections between said chambers and one of the parts whose movements are to be synchronized with another, pressure-operated means having connection with said valves, and means controlled by variations in the relative speeds of the parts to be synchronized for controlling the operations of said pressure-operated means, said means comprising a second pair of chambers having openings through which they may have communication with either of said air sources, valves in said second pair of chambers for controlling such communication, pressure-operated means connected to said valves, and means operated in consonance with the movements of the parts to be synchronized for controlling the operation of the pressure operated means of the valves in the second pair of chambers, a third pair of chambers having openings through which they may have communication with either of the air sources, valves for controlling such communication and pressure-operated means connected to said valves, means controlled by the valves in the second pair of chambers for controlling the operations of the valves in the third pair of chambers, and means controlled by the operations of the valves in the third pair of chambers for controlling the operation of the valves in the first pair of chambers.
82. Mechanism for synchronizing the operations of moving parts, comprising a fluid-operated motor for one of said parts, a governor valve for controlling the operation of said motor, a pair of independently operable pneumatics, connections between said pneumatics and valve, said connections including elements which are operable independently of each other from the respective pneumatics, and means for operating said pneumatics severally under control of variations in the relative speeds of the moving parts which are to be synchronized.
83. Mechanism for synchronizing the operations of moving parts, comprising a fluid-operated motor for one of said parts, a governor valve for controlling the operation of said motor, a pair of independently-operable pneumatics, connections between said pneumatics and valve, including an oscillatory lever having connection with said valve, intermediate connections between the lever and the respective pneumatics, said connections being separately operable whereby one of the pneumatics oscillates the lever in one direction and the other pneumatic oscillates the lever in the other direction and the action of neither pneumatic is resisted by the other.
84. Mechanism for synchronizing the op-

- erations of moving parts, comprising a fluid-operated motor for one of said parts, a governor valve for controlling the operation of said motor, a pair of bellows, means for operating said bellows severally under control of variations in the relative speeds of the moving parts which are to be synchronized, an oscillatory shaft, means whereby the shaft is oscillated in opposite direction by the respective bellows, an oscillatory lever having connection with the valve, and connections for oscillating said lever from said shaft.
85. Mechanism for synchronizing the operations of moving parts, comprising a fluid-operated motor for one of said parts, a governor valve for controlling the operation of said motor, and means for moving the governor valve in opposite directions to increase or decrease the speed of the motor, comprising chambers each having communication with sources of air of different pressures, valves in said chambers for controlling said communication, pressure operable elements connected to said valves, valves for controlling the pressures exerted upon said pressure operable members, and means for operating the latter valves selectively and in accordance with the respective speeds of the parts to be synchronized, said means including a valve-actuating member, and means controlled in accordance with the speeds of the parts to be synchronized for moving said actuating member into engagement with one or the other of said valves and causing it to open the valve with which it is engaged.
86. In a mechanism for synchronizing the operations of parts, the combination with a tracker board having a special aperture, and a controller having spaced apertures arranged to register with said special aperture, of mechanism including a series of chambers having openings through which they may have communication with air sources of different pressures, and valves for controlling such communication, said mechanism also including pressure-operable members for operating said valves and connections between certain of the chambers and one of the moving parts to be synchronized, and further including means having openings through which air may be admitted to the pressure operable members in the last named chambers, valves for the last named openings and means controlled from others of the chambers for operating said valves; said mechanism also including air conduits having communication with the special aperture of the tracker board and through which certain of the pressure-operable members are simultaneously subjected to atmospheric pressure under control of said controller and a valve arranged to control the admission of atmospheric air to another of the pressure-operable members, and an op-

erating means for the last named valve arranged to move in consonance with the other part to be synchronized.

87. Mechanism for synchronizing the operation of a sound producing instrument and a moving shaft, comprising a motor, a pair of controlling valves, and means whereby the movement of said valves effects an increase or decrease in the speed of the motor 10 according to which of the said valves is actuated first, pneumatic means for actuating said valves and controllers acting under control of the moving parts respectively, for controlling the pneumatic forces to said 15 means, one of said controllers comprising a circuit closing element bodily movable with the said shaft, an electric circuit periodically closed thereby, a magnet in said circuit and a valve actuated by said magnet.
- 20 88. In a mechanism for synchronizing the operations of a sound-producing instrument and a shaft, a mechanism having pressure-operable members, connections between said members and the sound-producing instrument, and openings through which said members may be exposed to atmospheric pressure, combined with means operated in consonance with the sound-producing instrument and shaft respectively for controlling 25 said openings, one of said means comprising a switch movable in consonance with the shaft, a valve operatively related to one of said openings and electrical connections between said valve and switch.
- 30 89. In a mechanism for synchronizing the operations of a sound-producing instrument and a shaft, a mechanism having pressure-operable members, connections between said members and the sound-producing instrument, and openings through which said members may be exposed to atmospheric pressure, combined with means operated in consonance with the sound-producing instrument and shaft respectively for controlling 35 said openings, one of said means comprising a rotatable switch movable in consonance with the shaft and having its outer surface provided with conducting and non-conducting portions arranged alternately, 40 said conducting portions being connected with each other by a conductor, contact arms arranged to bear on the outer surface of the

switch, an electro-magnet, a valve for closing one of said openings arranged to be operated by said magnet, a source of supply 55 of electrical connections and electrical energy between the latter, the magnet and the contact arms.

90. In a mechanism for the operation of a record-controlled pneumatically-operated 60 sound-producing instrument and the shaft of another instrument, comprising, in combination with the pneumatic motor for the first named instrument and a governor valve for controlling the speed of said motor: a 65 synchronizing means having connection with the valve, and including pneumatically operable valves, and connections between said valves and the sound-producing instrument and shaft, respectively, said connections controlling the valves and one of the same including a duct to be opened and closed in consonance with the movement of the record of the sound-producing instrument, the other connection including an electrical contact 70 movable in consonance with the shaft, an electromagnet, and electrical connections between the contact and magnet.

91. Mechanism for synchronizing the operation of moving parts comprising, in combination, primary controlling elements operated in accord with the parts to be synchronized, a motor for one of the said parts and connections between the motor and the primary controlling elements, including an 85 electro-magnet, electrical connections between the magnet and one of the primary controlling elements, a chamber, a valve movable in said chamber, sources of air of different pressures, said chamber having 90 ports through which it may have communication with either of said sources under control of the valve, a pressure actuated operating means for the valve and means controlled by the magnet for admitting pressure to said operating means.

In testimony whereof I have hereunto set my hand in presence of two subscribing witnesses.

EDWIN WELTE.
